UNITED STATES PATENT OFFICE

145,920

DESIGN FOR A GLIDER

Peter V. Armstrong, Warren, Ohio, assignor to
Federal Machine and Welder Company, War-
ren, Ohio, a corporation of Ohio

Application December 13, 1945, Serial No. 124,678

Term of patent 7 years

(Cl. D15—11)

To all whom it may concern:

Be it known that I, Peter V. Armstrong, a citizen
of the United States, residing at Warren, in
the county of Trumbull and State of Ohio, have
invented a new, original, and ornamental Design
for Gliders, of which the following is a specifica-
tion, reference being had to the accompanying
drawing, forming part thereof.

In the drawing:

Figure 1 is a perspective view of a glider show-
ing my new design,

Figure 2 is a top plan of the glider, on a smaller
scale, and

Figure 3 is an end elevational view of the glider.

The characteristic features of my design reside
in the portions shown by means of full lines in
the drawing.

I claim:

The ornamental design for a glider, substan-
tially as shown and described.

PETER V. ARMSTRONG.
